Fig. 10.

UNITED STATES PATENT OFFICE.

ALBERT R. LOCKE, OF CHICAGO, ILLINOIS.

ELECTRIC SWITCH.

Application filed May 21, 1921. Serial No. 471,339.

To all whom it may concern:

Be it known that I, ALBERT R. LOCKE, a citizen of the United States, residing at Chicago, in the county of Cook and State of Illinois, have invented certain new and useful Improvements in Electric Switches, of which the following is a specification.

This invention relates to electric switches.

It will be explained as applied to a switch 10 for switchboard use although it may be employed in various other fields and on other fixtures.

One of the objects of the invention is to provide an improved switch.

15 Another object is to provide an improved knife switch whose movable contact is normally biased to mid-position and firmly held in its extreme positions without dependence upon the frictional or spring action of the contacts.

Another object is to provide a switch which may be secured in position without the use of extraneous fasteners such as bolts, screws and the like.

25 Another object is to provide a switch which is automatically and quickly operated from extreme to mid-positions after the operation is initiated.

Another object is to provide a switch 30 which may be readily and quickly installed and removed.

Another object is to provide a switch which may be selectively controlled in groups or gangs.

35 Another object is to provide a switch which is neat in appearance, inexpensive to manufacture, and reliable and efficient in operation.

Other objects and advantages will hereinafter appear.

Embodiments of the invention are illustrated in the accompanying drawings.

The views in the drawings are as follows:

Fig. 1 is a horizontal central section 45 through one form of switch in position on a switchboard.

Fig. 2 is a vertical central section thereof.

Fig. 3 is a section on the line 3-3 of Fig. 2.

50 Fig. 4 is a section on the line 4-4 of Fig. 1.

Fig. 5 is a section on the line 5-5 of Fig. 2.

Fig. 6 is a horizontal central section of

a modified switch particularly adapted for 55 selective group or gang control.

Fig. 7 is a vertical section through the modified switch in selected condition.

Fig. 8 is a section on the line 8-8 of Fig. 7. 60

Fig. 9 is a vertical section through the modified switch in non-selected condition.

Fig. 10 is a side view of the modified switch in one of its extreme positions.

Fig. 11 is a front elevation of a switch- 65 board equipped with the improved switch and adapted for selected group control, and

Fig. 12 is a section on the line 12-12 of Fig. 11.

Figs. 1 to 5 will first be described. 70

The switch is shown mounted upon a switchboard of the so-called "dead front" type. Such switchboards ordinarily have a back board or panel 1 of suitable insulating material and a front plate or panel 75 2 of metal. The back board carries the fixed switch contacts and terminals while the front plate is insulated therefrom and is primarily for the purpose of protecting the operator from coming in contact with 80 the "live" parts.

The improved switch comprises, in general, two alternate sets of fixed contacts 3 and 4, a movable contact 5, a support 6, and an operating handle 7. 85

The support comprises a cylindrical member 8 provided at its rear end with a diametrical slot 9. The forward end of member 8 is of smaller diameter than the rear end, to form an annular shoulder 10, and is exteriorly threaded. The forward end is also provided with an open ended substantially hemispherically bottomed cylindrical chamber 11. Slot 9 extends into or 90 communicates with chamber 11.

The decreased diameter and internal chamber cause the forward end of the support to take the form of a projecting ring 12. The forward edge of ring 12 is provided with two diametrically positioned 100 notches 13. Notches 13 extend through the rim of ring 12 in a direction at right angles to slot 9.

Secured to handle 7 is an actuator 14, having a substantially spherical head which 105 movably fits within chamber 11 of the support. The head of the actuator is provided with a hole 15 which extends axially

from its base to a point above the center thereof. The head also has a small pivot hole extending therethrough at its center and at right angles to hole 15. The pivot 5 hole receives a pivot pin 16. The actuator is pivoted slightly eccentric. This construction may be secured by the hole 15 and, if desired, by flattening slightly the bottom of the head about hole 15.

10 The movable contact of the switch includes a flat blade 17 pivotally connected to actuator 14 by pin 16. Blade 17 may be made of suitable metal such as steel or iron. The blade does not carry current so that the 15 conducting properties of the metal composing the same is of no importance. The rear end of blade 17 is slotted to receive and hold a screw 18. An insulating bushing 19, having a cylindrical hole therein, fits upon 20 the end of blade 17 and is held in place by a nut 20 which threads upon screw 18. Bushing 19 carries a metallic ferrule or sleeve 21 which may be secured thereto in any suitable manner, such for example, as 25 by spinning the end thereof into the bushing.

The portion of ferrule 21 which is principally depended upon for carrying the current between the set of fixed contacts, 30 is back of the left hand or rear edge thereof. The rear edge, however, is the first and last point to meet and leave the fixed contacts. Therefore, in addition to obtaining a good wiping contact, the point where arc- 35 ing is most apt to occur is not depended upon primarily to carry the current. The usual pitting and burning of the movable contact with accompanying poor electrical conductivity is thus eliminated from the 40 main current carrying portion and is thus rendered largely unobjectionable. The ferrule is also readily rotatable so that different parts of its surface may be brought into engagement with the fixed contacts.

45 Ferrule 21, when the switch blade is in either of its extreme positions, is forced between the set of fixed contacts 3 or 4, respectively. Thus the respective set of fixed contacts is electrically interconnected by the 50 conducting ferrule of the movable contact.

The actuator, and consequently the movable contact and handle are biased to mid-position and firmly held in either extreme position by a pair of spring pressed plungers 22. These plungers are contained within two small holes which extend from the rear end of the support through the hemispherical bottom of the chamber thereof, one on each side of slot 9. Each plunger 55 is yieldingly forced against the spherical head of actuator 14 by a spring 23. The rear of the plunger holes are closed and the tension of the springs may be regulated by adjusting screws 24.

60 Blade 17 is further held in mid-position

and also in both extreme positions by two sets of balls 25 and 26, respectively. These balls are each retained in a hole which extends through member 8 and opens into slot 9. The balls are pressed inwardly toward 70 the slot by springs 27. Springs 27 are retained in place by threaded adjusting screw plugs 28. The distance between the sets or pairs of oppositely positioned balls is such that when blade 17 is in mid-position the 75 balls of each pair bear respectively against the upper and lower edges of the blade. Thus when the blade is moved toward either of its extreme positions sufficient force must be exerted to push inwardly either the upper or the lower set of balls. The balls therefore hold the switch blade and handle in mid-position. When the blade is moved to one of its extreme positions, where the contact carried thereby interconnects one of 80 the pairs of fixed contacts, either the lower or upper set of balls lies back of the opposite edge of the blade holding the same in extreme position. To move the blade from extreme position sufficient force must be 85 used to depress the balls so that the blade may be moved over them. Thus the balls snap behind the edges of the switch blade and assist in holding the same against premature movement, either from mid-position 90 or extreme position.

The support is held to the front plate of the switchboard and the actuator and blade are held to the support by an internally threaded nipple 29. This nipple screws 100 upon the threaded ring 12 of the support, clamping the front plate against shoulder 10 and closing the pivot notches in ring 12 so that the actuator is firmly held in the support chamber.

The circular projecting ring of the switch support permits the drilling of circular holes in the front plate of the switchboard and the holding nipple firmly secures the switch together and to the switchboard in 110 an exceedingly simple and attractive manner. The handle is pivoted in or in front of the plane of the front panel which need not be slotted to allow for the movement of the handle.

If it is desired to more firmly secure the switch to the switchboard L shaped supporting feet 30 may be provided. These feet may be screwed or bolted to support 8 and the backboard, or they may be formed integrally with the support.

The operation of the switch is briefly as follows:

Normally the handle and movable blade stand in mid-position, as shown in the drawing. Neither set of fixed contacts is interconnected and the switch is open. The blade and handle are yieldingly held in mid-position by the spring pressed plungers acting 125 on the bottom of the spherical head of the 130

actuator and by the spring pressed balls acting against the upper and lower edges of the blade.

To close the switch through the upper or lower set of fixed contacts the handle is moved respectively downwardly or upwardly. As the head of the actuator is moved about its axis the eccentric pivoting thereof and the pressing back of the balls by the blade cause enough resistance to this movement to insure smooth and positive operation. Also, in case the handle should be released, the actuator, blade and handle will be returned automatically to mid-position where the exterior surface of the spherical head is nearest to the pivotal axis. When the handle is moved to such an extent that the spherical surface engaged by the plungers is again nearer the axis and the upper or lower pair of balls are back of the opposite edge of the blade, the force of the plungers and balls holds the handle, actuator and blade in this position. The fixed contacts are so related to the movable contact that in this condition the movable contact has been forced between one of the sets of fixed contacts interconnecting the same and completing the circuit. The retention of the switch in closed position is, therefore, independent of the frictional or spring engagement of the fixed and movable or current carrying contacts.

To open the switch it is only necessary to move the handle through an exceedingly small distance (only sufficient to move the spherical head of the actuator so that the curved cam acting surface thereof begins to allow the plungers to rise and the edge is past the pair of balls which have been behind the same), whereupon the spring pressed plungers automatically force the handle, actuator and blade to mid-position.

Figs. 6 to 10, inclusive, show a switch embodying the same principles and adapted for selective group or gang operation.

The switch has a slotted cylindrical support 35 containing an actuator 36 pivoted thereto by a pin 37. The support contains a pair of spring pressed plungers 38 and 39 which act upon the head of actuator 36 and two pairs of spring pressed balls 40 and 41 which act upon the switch blade. The actuator has an operating handle 42 secured thereto. A threaded nipple 43 holds the support to the switchboard and the actuator to the support. The foregoing structure is substantially the same as that hereinbefore described and functions in the same manner.

60. A movable blade 44, carrying a movable contact 45 similar to that previously described is held in a hole in the head of actuator 36 by pin 37 as in the previously described structure. Blade 44, however, instead of being formed of a single strip is

made up of two parallel spaced-apart metal strips 46 and 47. A selecting plunger 48 is positioned between strips 46 and 47. This plunger may be made of a flat strip of metal having an elongated hole 49 therein for the passage of pivot pin 37. The elongated hole allows the blade to be moved in and out as will be hereinafter described.

Plunger 48 has an attenuated extension 50 which extends thru an axial hole in handle 42. The hole in the handle is enlarged to form a cylindrical spring chamber in which is a spring 51. A selecting button 52 is secured to extension 50 so that it may be freely rotated thereupon but longitudinal movement of the button moves the selecting plunger longitudinally. Spring 51, bearing against the bottom of the hole in handle 42, and against the base of button 52, biases the button toward its outermost position, as shown in Fig. 9. The button and plunger, however, may be moved and retained in their innermost position by a pin 53 on the button and a bayonet slot 54 in the handle. When the button is forced in against the pressure of spring 51 and given a slight amount of rotation determined by the pin and slot, the button and selecting plunger are held in this position until the button is turned so that the pin is released.

The rear end of plunger 48 is pointed and lies between two pawls or dogs 55 and 56. Pawls 55 and 56 lie between strips 46 and 47 composing compound switch blade 44 and are pivoted thereto by pins 57 and 58, respectively. The front ends of pawls 55 and 56 are biased together by a spring 59. When button 52 and selecting plunger 48 are in outward position, as shown in Fig. 9, the two pawls are biased by spring 59 to assume a substantially parallel position, wherein neither materially projects beyond the edges of blade 44. When button 52 is forced in, the point of plunger 48 separates the forward ends of pawls 55 and 56 against the force of spring 59 and holds the same in this position with the forward ends of the pawls projecting slightly beyond edges of blade 44 as shown in Figs. 7 and 10.

In the extreme position of blade 44 and handle 42 movable contact 45 bridges and interconnects sets or pairs of stationary contacts 60 or 61, respectively.

A trip rod 62, having a pair of trip pins or arms 63 and 64 for each switch, cooperates with pawls 55 and 56 to cause the switch blade to move from either fixed position to mid-position. When button 52 is forced in to separate the front ends of pawls 55 and 56, as shown in Figs. 7 and 10, the front ends of these pawls are in the path of arm 63 or 64, depending upon whether the switch handle and blade are in one extreme position or the other. Thus, if as shown by the full lines of Fig. 10, the handle is down and the

blade and movable contact up, the front end of pawl 55 is in the path of arm 63 when trip rod 62 is depressed. On the other hand, if the handle is up and the blade and movable contact down, as shown by the dotted lines, then pawl 56 is in the path of arm 64 when trip rod 62 is elevated. When the selecting button and plunger are out the pawls are not in the path of either arm 63 or 64 in either extreme position of the handle and switch blade.

Consequently when the selecting button is in and the switch is moved to either extreme position the up and down movement of trip rod 62 will cause the arm thereon to engage the projecting ends of the pawls and trip the switch which will be moved to mid-position by its spring pressed plungers. When the button is out the movement of the trip rod does not affect the switch.

Figs. 11 and 12 diagrammatically show how the switches may be controlled by groups.

The switches in the right hand row are designated A, B, C, D, E and F, respectively, and since all of the rows may be similarly controlled, this row is chosen to illustrate the selective operation.

The trip rod is shown extending the height of the switchboard and biased to mid-position by two opposing springs 65 and 66. A pivoted lever 67 is connected to trip rod and may be operated either to elevate or depress the same.

Switch A has its selecting button out and its handle moved to close the upper step of contacts 60. Switches B and D are in mid-position. Switches C and F have their selecting buttons in and their handle depressed to close the upper set of contacts 60. Switch E has its button in and its handle thrown to close the lower set of contacts 61. Thus the switches A to F, inclusive, have been selectively operated to close a group of circuits and are set to be tripped to open the circuits in a predetermined manner. If trip lever 67 is raised switch E will be caused to open. No effect will be exerted upon the other switches. If the trip lever is depressed switches C and F will be caused to open. Switch A, however, since its button is out is unaffected. Any other combination of operations may be set up and tripped as desired.

All of the trip rods may be controlled together by providing means for simultaneously throwing all of the trip levers. One arrangement for accomplishing this result is to provide a pair of master trip bars 68 and 69 which extend along the switchboard and respectively above and below all of the trip levers. Moving the master trip

bars in one direction elevates all of the trip levers while moving the same in the other direction depresses all of the trip levers.

The switches may be connected to circuits as desired and by the selective operation of the same the circuits may be closed in various groups. By presetting the selecting plungers the switches may be tripped and the circuits opened in any desired group arrangement without affecting those switches and circuits which should remain closed. The selecting buttons give ready visual indications of the setting of the switches so that an operator can tell at a glance which switches will be open and which switches will remain closed upon the next operation of the trip lever.

Having described my invention what I claim as new and desire to secure by Letters Patent, is:—

1. An electric switch comprising a slotted support for attachment to a fixture, a substantially spherical actuator pivotally carried by the support, a pair of spring pressed plungers acting on opposite sides of the actuator, a lever carried by the actuator to move in the slot in the support, a movable contact carried by the lever, and a fixed contact cooperating with the movable contact.

2. An electric switch having a support for insertion through the wall of a fixture, said support being slotted at its rear end and screw threaded at its forward end, an actuator pivotally connected to the support, a movable contact carried by the actuator, a spring pressed plunger acting upon the actuator, and a threaded collar for attachment to the threaded end of the support and acting to hold the support to a fixture and to secure the actuator to the support.

3. An electric switch having a support with a threaded forward end for insertion through the wall of a fixture, a switch blade pivotally associated with the support and having an operating handle, and a threaded nipple for clamping the support to a fixture and securing the switch blade to the support.

4. A switch having a support for attachment to a switchboard, a contact carrying blade pivotally mounted on the support, and capable of being moved to a normal position and an extreme position, a handle for actuating the blade, a pair of pawls pivoted to the blade and movable to operating and non-operating position, a selector for controlling the position of the pawls, and means for cooperating with the pawls in operating position to cause the blade to be moved from extreme to normal positions.

In testimony whereof I hereunto subscribed my name.

ALBERT R. LOCKE.
